CLAIM

I claim the ornamental design for a right arm or left arm sectional, as shown and described.

DESCRIPTION

FIG. 1 is a front perspective view of a right arm or left arm sectional of Applicant's design;

FIG. 2 is a front elevational view thereof;

FIG. 3 is a rear elevational view thereof;

FIG. 4 is a first side elevational view thereof,

FIG. 5 is a second side elevational view thereof, the second side being opposite the first side;

FIG. 6 is a top plan view thereof; and

FIG. 7 is a bottom plan view thereof.

FIG. 8 is a front perspective view of a second embodiment of a right arm or left arm sectional of Applicant's design, the second embodiment being a mirror image of the first embodiment;

FIG. 9 is a front elevational view thereof;

FIG. 10 is a rear elevational view thereof;

FIG. 11 is a first side elevational view thereof;

FIG. 12 is a second side elevational view thereof, the second side being opposite the first side;

FIG. 13 is a top plan view thereof; and,

FIG. 14 is a bottom plan view thereof.

Where included, broken lines showing environment or structure are for illustrative purposes only and form no part of the claimed design.
